UNITED STATES PATENT OFFICE.

MONTREVILLE RUSSELL WILCOX, OF MINNEAPOLIS, MINNESOTA.

CLOSET.

1,090,508.

Specification of Letters Patent. Patented Mar. 17, 1914.

Application filed November 9, 1912. Serial No. 730,502.

To all whom it may concern:

Be it known that I, MONTREVILLE RUSSELL WILCOX, a citizen of the United States, and resident of Minneapolis, Hennepin county, Minnesota, have invented certain new and useful Improvements in Closets, of which the following is a specification.

My invention relates to portable closets adapted for general use and particularly designed for use in connection with school rooms.

The object of my invention is to provide a closet of simple, durable, and sanitary construction and one which will be positively sealed at the seat opening.

A further object is to provide a closet having a receptacle of economical construction and one that can be easily removed and provided with means for covering and concealing the contents before and during removal.

Other objects of the invention will appear from the following detailed description.

The invention consists generally in various constructions and combinations, all as hereinafter described and particularly pointed out in the claims.

In the accompanying drawings forming part of this specification, Figure 1 is a front elevation of a chemical closet embodying my invention, Fig. 2 is a side elevation of the same, Fig. 3 is a vertical sectional view, Fig. 4 is a detail sectional view of the cover and seat, Fig. 5 is a plan view of the seat with the cover raised, Fig. 6 is a detail sectional view with the cover raised.

In the drawing, 2 represents a casing, preferably of sheet metal having its exterior surface ornamented in any suitable manner, as by graining, embossing, or paneling, and provided with a front or forward wall 3 hinged at 4 to swing outwardly and expose the interior of the casing. The wall is preferably provided with a strap 5 having sockets formed therein to receive the downwardly turned ends of legs 6 upon which a foot rest 7 is mounted. These legs and the foot rest are removable from the door, whenever desired. Beneath the foot rest I prefer to provide a series of ventilating openings 8 for the admission of air to the casing. Within the casing is a receptacle 9, preferably of sheet metal, having handles 10 at each end and an opening 11 that is closed by a slide 12.

13 represents a sheet metal cover or top for the casing 2, having an opening 14 there-

in, a flange 15 being turned up out of the metal around said opening. A plate 16, preferably of wood, is fitted over the top 13 and provided with an opening registering with the opening in the top, with the edges of the opening fitting snugly against the flange 15. Within the opening in the casing-top and plate 16 I prefer to arrange a ring 17, T-shaped, substantially, in cross section, by means of inwardly and outwardly projecting flanges 18 and 19, the flange 19 extending over the joint between the flange 15 and the plate 16 and covering and concealing the same. Screws are provided, passing through the ring 17 in the flange 15 and into the wooden plate 16, thereby securing the parts together and sealing the joint between the ring and the top of the casing.

A seat 20 is hinged at 21 on the ring 17 and has a plate 22 set into its under surface at the front of the seat and provided with plugs 24 which register with holes 25 in the inwardly projecting flange 18. A cover 26 is hinged at 27 on an arm 28 and is provided with an annular recess 29 adapted to receive a hollow rubber gasket 30, which depends below the cover and is adapted to contact with the outwardly projecting flange 19, forming therewith a complete seal for the seat and the receptacle in the casing. The gasket 30 is made oval in cross section and fits snugly within the recess 29, and when the cover is dropped the gasket will strike the flange 19 and be slightly flattened by the blow and take up the shock without allowing the cover or the walls of the recess 29 to contact with the flange 19. Thus contact of metal with metal is prevented. The dropping of the cover will be practically noiseless and a perfect seal will be formed between the gasket and the flanged ring.

The cover, when closed, will completely encircle the seat and seat opening and the gasket between the cover and the top of the casing will seal the joint and thoroughly seal the receptacle. As the cover drops upon the metallic surface, there will be no possibility of the seal being broken through warping or cracking of a wood surface or unequal wear thereof. The metallic flange or other metal surface which may be employed, will at all times present a flat, uniform surface to the seat and the cover and a perfect seal will therefore be obtained under all conditions.

I may modify the form of the flanged ring and in various ways I may change the construction of the cover and still provide for its encircling the seat opening and seat and sealing the same.

At the rear of the cover I prefer to provide a vent pipe 31 communicating with the chimney or foul air flue. A circulation of air will thereby be maintained through the 10 casing from the holes 8 and when the cover 26 is closed there will be a perfect seal around the seat opening. Whenever desired, the door at the front of the cabinet may be opened, the slide closed, and the 15 receptacle drawn out.

In using the device, a quantity of water containing some germicidal solution will be placed in the receptacle. This feature, however, I make no claim for in this case, my 20 invention residing particularly in the construction of the casing and the perfect seal formed around the seat opening by the simple device shown and described.

I claim as my invention:—

25 1. The combination, with a plate having a seat opening therein, of a ring fitting within said opening and secured to said plate, said ring having inwardly and outwardly projecting flanges, a seat hinged to said inner flange on one side of said opening and having a bearing on said inner flange on the opposite side of said opening, a hinged cover, a gasket mounted in the underside of said cover and arranged to bear on said outwardly projecting flange when the cover is closed and encircle and seal said seat opening and said seat.

40 2. A closet comprising a metallic casing having a top provided with an opening therein, a plate fitting over said top and also having an opening co-inciding with the opening in said top, the metal forming the edge of the opening in said top being upwardly turned and secured to the edge of 45 the opening in said plate, a ring fitting within the opening in said plate and having an outwardly projecting flange overlapping and concealing the joint between said ring and plate, a seat hinged to said ring on one 50 side of said opening and having a bearing on said ring on the opposite side of said opening, said flange projecting outwardly beyond said seat, a hinged cover, a gasket provided in the underside of said cover and

adapted to contact with said flange when the cover is closed and encircle and seal said seat and said opening.

3. A closet comprising a casing having a seat opening in the top thereof, a metallic ring fitting within said opening and having an outwardly projecting annular flange overlapping and concealing the joint between said ring and the edge of said opening, a seat hinged to said ring on one side of said opening and having a bearing on said ring on the opposite side of said opening, said flange projecting outwardly beyond said seat and provided with outwardly and upwardly projecting arms, a cover hinged on said arms, and a gasket mounted in the underside of said cover and adapted to contact with said flange and encircle and seal said seat and said seat opening.

4. A closet comprising a casing having a top provided with a seat opening, a ring fitting within said opening and secured to the edges thereof and provided with an outwardly projecting annular flange adapted to rest on the top of said casing, a seat hinged to said ring on one side of said opening and having a bearing upon said ring on the opposite side of said opening, a hinged cover, and a gasket mounted in the underside thereof and adapted to contact with said flange when the cover is closed and encircle and seal said seat and said seat opening.

5. A closet having a top provided with a seat opening encircled by a metallic top-facing plate, a seat hinged at one side of said opening, a cover encircling said seat and spaced therefrom at the top and sides of the seat and hinged at one side of the seat opening, and a gasket interposed between the lower edge of the cover and the metallic top-facing plate and encircling the seat so as to prevent contact between the lower edge of the cover and the metallic top-facing plate and constitute a seal around the seat and the opening in the closet top, substantially as described.

In witness whereof I have hereunto set my hand this 21st day of October, 1912.

MONTREVILLE RUSSELL WILCOX.
